UNITED STATES PATENT OFFICE.

CHARLES WILLIAM GREEN, OF NEW YORK, N. Y., ASSIGNOR TO WESTERN ELECTRIC COMPANY, INCORPORATED, OF NEW YORK, N. Y., A CORPORATION OF NEW YORK.

SIGNALING SYSTEM.

Application filed December 17, 1921. Serial No. 523,006.

To all whom it may concern:

Be it known that I, CHARLES WILLIAM GREEN, a citizen of the United States, residing at New York city, in the county of 5 Bronx, State of New York, have invented certain new and useful Improvements in Signaling Systems, of which the following is a full, clear, concise, and exact description.

10 This invention relates to signaling systems and more particularly to repeating systems in which signals of different types or frequencies are desired to be repeated with different degrees of amplification.

15 The preferred form of this invention will be hereinafter described in detail in connection with a two-way telephone repeater of the relayed ringing type in which a source of calling currents is connected to one line 20 section when incoming calling currents are received from the other line. Such a repeating system has sometimes been found to have such a degree of amplification for ringing currents that incoming ringing currents in one line section would pass through 25 the repeater and cause the false operation of the ringing current responsive means associated with the other line section,—a result which is, of course, undesirable.

30 In accordance with this invention the false operation of the ringing responsive means is prevented by providing means for reducing the amplification of the ringing currents to such an extent that the currents of the ringing frequency which tend 35 to pass through the repeater, are of negligible or practically zero amplitude, while still maintaining the desired repeater gain characteristic for those frequencies of importance in speed. This means preferably 40 comprises a series resonant circuit connected across the input leads of the repeater or across the midpoints of each three-winding transformer and tuned to the frequency it is desired to suppress; or it may comprise 45 an anti-resonant circuit in series with the input leads and tuned to that frequency. If the ringing currents are of 135 cycles, for example, this resonant circuit, should be tuned to that frequency. This invention, in the 50 case above described, is also preferably employed in connection with the usual series

condensers present in the line, for reducing the intensity of the ringing currents prior to impressing them on the tuned circuit and 55 the repeater. It has been found that the use of this resonant circuit does not appreciably interfere with the repeater gain correcting means such as that described, for example, in Casper application Serial No. 60 366,581, filed March 17, 1920, which has become Patent 1,530,648, so that the simultaneous use of the correcting means of this invention and that of Casper producer a practically flat repeater gain characteristic 65 from 200 or 300 cycles to 2000 cycles, with a negligible repeater gain for 135 cycle currents.

This invention will be better understood 70 by reference to the following detailed description taken in connection with the accompanying drawing, in which Fig. 1 illustrates schematically this invention embodied in a 22 type telephone repeater circuit employing relayed ringing; and Fig. 2 is a 75 modification thereof.

The signaling system disclosed in Fig. 1 comprises two line sections 10 and 11 between which may be connected a 22 type repeater circuit comprising an amplifier 12 for 80 amplifying currents from line section 10 and amplifier 13 for amplifying currents from line section 11. The amplifying elements shown are of the well-known vacuum tube 85 type and it is not thought necessary to give herein a detailed description of their method of operation.

Line section 10 is shown as terminating in a three-winding transformer 14 and an appropriate balancing network 15, while line section 11 is terminated in a similar three-winding transformer 16 and a balancing network 17. The midpoints of the three-winding transformer 14 are connected to the input terminals of the amplifier 12 through 90 leads which include a gain adjusting potentiometer 18 and an input transformer 19. Similarly, the midpoints of the three-winding transformer 16 are connected to the input terminals of amplifier 13 through 95 leads including a corresponding gain adjusting potentiometer 20 and input transformer 21. The output terminals of each of the amplifiers are connected through a Camp-

bell wave filter to the third winding of one of the three-winding transformers. From this brief description, it will be apparent to those skilled in the art that incoming signalling currents, such as speech currents from line section 10 will be impressed through input transformer 19 upon amplifier 12 thereby being amplified before being impressed upon the other line section 11. Similarly, 10 any incoming speech currents from line section 11 will be received by the amplifier 13 through the intermediary of input transformer 21 and will be amplified before being impressed on line section 10.

15 In case it is desired to relay the ringing or calling currents of the telephone system around the repeaters 12 and 13 instead of allowing them to be amplified in the same manner as speech currents, a relayed ringing arrangement may be employed, such, for example, as that shown in the Toomey Patent No. 1,364,159, issued January 4, 1921. This relayed ringing arrangement comprises, in brief, a ringing responsive relay 25 normally connected in shunt to line section 10. Incoming ringing currents from line section 10 will cause the energization of relay 25 and by obvious circuits will de-energize relay 26 and energize relays 27 and 28. The energization of relay 28 breaks the connection between the three-winding transformer 16 and line section 11, and connects instead, a suitable source of ringing currents to line section 11. In a similar manner, incoming ringing currents from line section 11 cause the energization of an alternating current relay 30 which produces successively by obvious circuits, the deenergization of relay 31 and the energization 40 of relays 32 and 33. Relay 33 on being energized, connects a suitable source of ringing current through the line section 10 while disconnecting the line section from the repeater. Relays 30 and 33 in operating, also serve to connect artificial networks 35 and 36 to the line side of the three-winding transformers in order to prevent the repeater circuit from being unbalanced during the ringing operation.

50 As described in the above mentioned Casper patent and the Whiting application Serial No. 406,861, filed August 30, 1920, which has become Patent 1,530,633, it has sometimes been found preferable to provide 55 means in the repeater circuit for giving the vacuum tube amplifier substantially a flat repeater gain characteristic over the entire range of frequencies of importance in speech. This result may be obtained by adjusting the transformer leakage to overcome 60 transformer capacity effects and the internal capacity of the associated repeater and by including a resistance 40 and a capacity 39 of the proper values in circuit 65 with the transformer. This arrangement, however, while giving the desired flat repeater gain characteristic over the range of frequencies of importance in speech, also serves to increase quite appreciably the amplification of the repeater of those frequencies below the speech range such as those normally used for ringing or calling currents, namely, of the order of 135 cycles. Heretofore, in repeater circuits of the relayed ringing type in which it is desired to 70 prevent the amplification of the ringing currents, it has been found sufficient for repeaters with low gains at ringing frequencies to merely include serially in each line section condensers such as those shown as 41, 42, 43 and 44 of the drawing, of such values as to have the necessary high impedance for the ringing currents while offering negligible impedance to the transmission of speech currents. This simple expedient, 80 however, has not been found sufficient for repeater circuits employing the improved means above described for giving the amplifier a flat gain characteristic curve. Due to the large gain of the repeater for 135 cycles, ringing currents of sufficient strength occur in the output circuit of each repeater to frequently cause the false operation of the ringing responsive relay associated with the other line section,—a result 85 which is, of course, highly undesirable.

90 In accordance with this invention, the gain of the repeater for ringing frequencies has been reduced and the false operation of the ringing responsive relay is prevented by 100 the connection across the input leads of each half of the repeater circuit of a series resonant circuit comprising an inductance 45 and a capacity 46 of such values as to maintain the input leads at substantially the 105 same potential for the frequency of the ringing currents while maintaining the desired potential difference therebetween for the frequencies of importance in speech. The use of this series resonant circuit has 110 been found particularly advantageous for the reason that its use produces no substantial alteration in the shape of the repeater gain characteristic curve for those frequencies greater than 135 cycles. For example, 115 in one case, a telephone repeater had a substantially constant gain of 23 miles for all frequencies between 135 cycles and 2000 cycles in the case where the shunt circuit 120 was not included. When the shunt circuit was included, the repeater had a substantially constant gain of 22½ miles for frequencies between 300 and 2000 cycles, while it had a gain of less than a mile for 135 cycles.

125 If desired, the correcting network for suppressing the signaling currents may comprise an anti-resonant circuit connected in series with the input leads and tuned to the signaling frequency. This arrangement 130

is shown in Fig. 2 where elements 48 and 49 constitute the anti-resonant circuit. In order to keep the circuit symmetrical, it will generally be preferable to duplicate elements 48 and 49 in the other side of the line as shown by elements 50 and 51.

In general, however, it will be found preferable to employ the series resonant circuit for the reason that it does not require the breaking of the input leads of the repeater but may be connected or disconnected at will without disturbing the operation of the repeater when it is desired to change the repeater from a through-ringing type to a relayed-ringing type or vice versa.

Another advantage derived from the use of the resonant circuit of this invention is that it aids in obtaining a satisfactory balance between the artificial balancing network 15 for example and the associated line 10. Line 10 when composed for example will have apparatus associated therewith which is difficult to balance because its impedance changes rapidly for frequencies in the neighborhood of 100 cycles. The reduction of the repeater gain for 135 cycles due to the resonant circuit obviates the necessity for as accurate a balance between line 10 and artificial line 15 for frequencies of the order of 100 cycles as for frequencies in the speech range.

When the series resonant circuit is employed, the inductance 45 should be made as small as is consistent with good quality transmission in order to reduce the D. C. resistance of the shunt circuit to a small value. On the other hand, inductance 48 should be made as large as is consistent with good quality transmission in order to make the impedance of the circuit as high as possible for the resonant frequency. It has been found, however, that if element 45 is decreased beyond a certain value and element 48 increased beyond a certain value that the elements produce an undesirable modification of the repeater gain characteristic for frequencies near the upper range essential to speech. When the frequency to be suppressed is in the neighborhood of 135 cycles, element 45 should preferably have a value of approximately one henry and element 48 approximately two henries.

Although this invention has been described above in connection with means for giving a vacuum tube repeater a substantially constant gain over the entire range of frequencies of importance in speech, it is obvious that this invention is not limited in its application to systems employing such means. It will also be apparent to those skilled in the art that this invention can be advantageously used in signaling systems widely different from the telephone repeater system described above wherein it is desired to suppress signals of a certain frequency while

permitting the through transmission of signals of other frequencies or types.

What is claimed is:

1. In combination, two line sections, a repeater circuit therebetween, a repeater element therein, a transformer in said circuit, means associated with said transformer for causing said element to have a substantially constant amplification over a wide range of frequencies which it is desired to transmit through said repeater, and means for preventing the passage of an undesired frequency through said repeater circuit without appreciably effecting the amplification characteristic of said element for said range of frequencies comprising an inductance and a capacity resonating at the undesired frequency.

2. In combination, two line sections, a repeater circuit therebetween comprising an amplifying element and a transformer, means associated with said transformer for causing said repeater to have a substantially constant amplification for the entire range of frequencies of importance in speech, and means for preventing the passage of an undesired ringing current frequency through said repeater circuit without appreciably effecting the amplification characteristic of said repeater for said range of frequencies, said means comprising a path effectively in shunt to a winding of said transformer and including an inductance and a capacity serially connected with respect to each other.

3. In combination, an amplifying repeater, means for giving said repeater a substantially constant amplification for all frequencies between 300 cycles and 2000 cycles, and means for making said repeater have an amplification of substantially zero for frequencies in the neighborhood of 135 cycles.

4. In combination, two line sections over which voice currents and ringing currents are adapted to pass, a link circuit comprising an amplifying repeater for interconnecting said lines, means for causing said repeater to have a substantially constant amplification characteristic over a wide range of voice frequencies, and resonating means for preventing the passage of ringing current to said repeater while maintaining substantially constant the amplification characteristic of said repeater for the voice currents.

5. A two-way repeating system comprising two uni-directionally transmitting electric space discharge wave amplifiers, each capable of transmitting the frequencies of a given frequency band with substantially uniform amplification over said frequency band, two circuits, one having an impedance more difficult to balance for frequencies near a given frequency in the neighborhood of said band than for other frequency regions, means, including impedance balancing networks for said circuits, connecting said amplifiers.

plifiers for transmitting in opposite directions between said circuits, and circuits, each including inductance and capacity tuned to said given frequency and so connected to said last mentioned means as to be capable of substantial discrimination against waves of said given frequency compared to waves of neighboring frequencies, both as regards

line-to-line transmission and as regards transmission around the loop comprising the 10 amplifiers.

In witness whereof, I hereunto subscribe my name this 14th day of December, A. D. 1921.

CHARLES WILLIAM GREEN.
